UNITED STATES PATENT OFFICE

122,575

DESIGN FOR A COMBINATION CONTAINER CAP REMOVER AND SCREW DRIVER

John B. Smiley, New York, N. Y.

Application June 24, 1940, Serial No. 93,214

Term of patent 14 years

To all whom it may concern:

Be it known that I, John B. Smiley, a citizen of the United States, residing at New York, in the county of New York, State of New York, have invented a new, original, and ornamental Design for a Combination Container Cap Remover and Screw Driver, of which the following is a specification, reference being had to the accompanying drawing, forming part thereof.

The figure is a perspective view of a combination container cap remover and screw driver, showing my new design.

I claim:

The ornamental design for a combination container cap remover and screw driver as shown.

JOHN B. SMILEY.
